CLAIM

We claim the ornamental design for a lighting fixture, as shown and described.

DESCRIPTION

FIG. 1 is a left elevation view of the lighting fixture showing our new design;

FIG. 2 is a right elevation view thereof;

FIG. 3 is a front elevation view thereof;

FIG. 4 is a rear elevation view thereof;

FIG. 5 is an enlarged top plan view thereof;

FIG. 6 is an enlarged bottom plan view thereof; and,

FIG. 7 is a perspective view thereof.

The broken lines depict portions of the lighting fixture that form no part of the claimed design.
